EMERGENCY DOOR OPENING TOOL

Joseph D. Tessier, Worcester, Mass.

Application September 16, 1939, Serial No. 295,331

9 Claims. (Cl. 254—131)

This invention relates to an improved device adapted to the use of the fire department, insurance emergency squad, building wreckers, or others, for opening locked doors with a minimum of damage and time expended, and for easily and quickly separating timber structures, partitions, and the like.

Objects of the invention include the provision of a tool for the above purposes; the provision of a prying implement quickly and easily adjustable so that a proper leverage may be obtained regardless of the angle at which the working edge is inserted into the members to be pried apart; the provision of an adjustable prying implement having a thin edge which may be inserted between the lock and the jamb of a door, to force the lock instead of breaking the door.

Other objects and advantages of the invention will appear hereinafter.

Reference is to be had to the accompanying drawing, in which:

Fig. 1 is a front elevation of a device embodying this invention;

Fig. 2 is a side elevation of the same;

Figs. 3, 4, and 5 are detail views of separate elements of the device.

Referring to the drawing, the numeral 10 denotes the head of the implement and comprises a thin edge 12 which is the prying or working edge, a wedge-shaped body 14, at one end of which the thin edge 12 is located, and at the wide end of which are two integral, spaced circular portions 16 of like design. These circular portions are provided with aligned slots 18.

The head 10 is pivoted at the center of the circular portions 16 by a pin 20 on a cooperating, and similarly shaped member 22 which is of a shape and size to fit between the portions 16. The member 22 is integral with a shank portion 24 which is provided with circular shoulders 26, cooperating with the peripheries of the portion 16. A slot 28 is located in the center part of the shank and extends past the shoulders 26 into the member 22 to a depth equal to the depth of slots 18. Thus it is seen that slots 18 may be aligned with slot 28 in a plurality of positions of adjustment of head 10.

A lug 30 is slidable in slot 28 and aligned slots 18 and is of such a size that when bridging these slots in their aligned positions, the head is locked relative to the shank 24, but when contained entirely within slot 28, back of the shoulders 26, the head 10 may be angularly adjusted about its pin 20. Each end of the lug 30 is provided

with a boss or projection 32, which extends laterally beyond the sides of the shank 24.

A stamped channel-shaped plate 34 is fitted to slidably reciprocate on the shank 24, and at its forward end is provided with apertures 36 to fit the projections 32. Thus the lug 30 will be reciprocated in slots 18 and 28, as the plate 34 is reciprocated. A tension spring 38 is fixed at one end to the shank 24 in a groove 40 to accommodate the same, and at its other end, 10 the spring is fixed to the sliding plate 34. Thus it is clear that the spring 38 tends to urge the lug 30 to locking position with respect to the head 10.

Thumb and finger pieces 44 are provided on the 15 sides of the plate 34 to assist in pulling the same rearwardly to unlock and allow for adjustment of the head 10. The plate 34 is guided and limited in its sliding movement by a pair of headed screws or bolts 46 working in slots 48 in the 20 plate and secured to the shank 24.

At the end of shank 24 remote from the head 10 there is provided a cylindrical handle portion 50 which is adapted to slidably receive a pipe-like member 52 which may act as an extension of the handle. A longitudinal groove 54 is provided in the pipe 52, this groove terminating short of the ends thereof. A screw or lug 56 extends outwardly from the handle 50 and is received in the groove 54 to prevent the member 52 from sliding off of the handle, and a circular shoulder 58 is provided on the shank to act as an abutment for the pipe-like member 52 in its movement in the opposite direction. A heavy knob 60 is provided on the end of the pipe 30 for extra weight.

In the operation of the device, the tool will ordinarily be adjusted so that the working edge 12 is in line with the handle 50, and the edge is inserted as far as possible between the members 40 to be pried apart. Then the pipe-like member 52 may be reciprocated so that the edge 12 will be hammered home, due to the action of the pipe on the abutment 58. When the tool is used to open a door or break a lock, the handle is 45 not in a position where leverage can readily be applied to the handle, and in this case, the plate 34 is slid back, the shank 24 and handle 50 pivoted about pin 20 to desired angular location, where merely by letting go of the plate 34, the 50 parts will be very solidly locked by the lug 30, and leverage may be easily applied to the handle. This adjustment takes but a few seconds, and immeasurably increases the applications and handiness of the tool.

Having thus described my invention and the advantages thereof, I do not wish to be limited to the details herein disclosed, otherwise than as set forth in the claims, but what I claim is:

- 5 1. In an implement of the class described, a handle having an enlarged shank, a laterally reduced circular portion at one end of the shank, said reduced portion having a concave shoulder, a prying implement having a convex portion co-
10 operating with said concave shoulder for angular movement with respect thereto, a series of notches in the periphery of said convex portion, a slot in said shank extending into said circular portion past the shoulder, a lug in said slot, 15 a spring normally urging said lug into engagement with a selected notch, a hand piece slidably mounted on the shank, and means connecting the lug and said hand piece, said spring being secured to said hand piece and to said shank.
2. An emergency door opening tool comprising a prying head having a sharp-edged wedge and a curved bearing surface for insertion between the parts to be pried apart, an elongated straight handle adjustably associated with said head, whereby said head and its wedge may be selectively located in alined position with respect to said handle and at an angle thereto, and means to lock said head and said handle in adjusted position, said means including a resiliently urged, manually retractible lug on the handle.
3. An emergency door opening tool comprising a prying head having a wedge for insertion between the parts to be pried apart, an elongated straight handle adjustably associated with said head, whereby said wedge may be selectively located in alined position with respect to said handle and at an angle thereto, and means to lock said head and said handle in adjusted position, said means comprising a series of notches in said head, a movable lug on said handle for engagement with any one of said notches, said lug extending through said handle and laterally beyond it at both sides, a hand-piece slidably mounted on said handle and engaging the laterally extending parts of said lug, and a spring connected between said hand-piece and said handle and urging the former, and therefore the lug, toward engagement with the notches in the head.
4. An emergency door opening tool comprising a prying head having a wedge for insertion between the parts to be pried apart, an elongated straight handle adjustably associated with said head, whereby said wedge may be selectively located in alined position with respect to said handle and at an angle thereto, and means to lock said head and said handle in adjusted position, said means comprising a series of notches in said head and a cooperating sliding lug in said handle, said lug extending laterally beyond both sides of said handle, a hand-piece embracing the handle on the exterior thereof, said hand-piece having means engaging the laterally extending ends of said lug, a spring in said handle to urge said hand-piece, and therefore said lug, towards the head and means on said handle for guiding said hand-piece and retaining it in position with respect to said handle.
5. An emergency door opening tool comprising a prying head having a wedge for insertion between the parts to be pried apart, an elongated straight handle adjustably associated with said head, whereby said wedge may be selectively located in alined position with respect to said handle and at an angle thereto, and means to lock said head and said handle in adjusted position, 5 said means comprising a rounded central extension on said handle, said head having a rounded portion cooperating with the rounded portion on the handle and having a central slot into which the rounded portion on the handle extends, means pivoting said rounded portions, a series of notches on the periphery of the rounded portion of the head, a lug slidable in the handle portion for selective engagement with any of said notches, said lug extending beyond the sides of the handle, 10 a hand-piece embracing at least three sides of said handle and having means at its forward end for engagement with the laterally extending parts of said lug, a recess in said handle, a spring secured at one end in said recess, and at its other end to said hand-piece for urging the hand-piece, and therefore the lug, to notch engaging position.
6. An emergency door opening tool comprising a prying head having a wedge for insertion between the parts to be pried apart, an elongated straight handle adjustably associated with said head, whereby said wedge may be selectively located in alined position with respect to said handle and at an angle thereto, and means to lock said head and said handle in adjusted position, 15 said means comprising cooperating rounded parts on said head and said handle, a series of notches in said head and a cooperating slidable lug in said handle, a slidable hand-piece on said handle and having means engaging said lug to move the same, 20 said hand-piece extending over at least three sides of said handle and being of an extent large enough to be easily grasped by an operator, and spring means urging said hand-piece toward the head.
7. An emergency door opening tool comprising a prying head having an elongated curved bearing surface and a sharp-edged wedge at the end thereof, a handle adjustably associated with said head, whereby the head and its wedge may be selectively located at an angle to, and in generally alined position with respect to said handle so that said curved surface substantially forms a continuation of a surface of said handle when the parts are alined, and means to lock said head and said handle in either position.
8. In an article of the class described, a head having a wedge, an elongated handle angularly adjustably mounted with relation to said head, whereby said wedge may be selectively located in substantially alined position with respect to said handle and at an angle thereto, means to lock said head in adjusted position comprising a lug located in said handle, and a sleeve embracing said handle and connected to said lug.
9. In an article of the class described, a handle, a prying member rotatably adjustable with respect thereto, cooperating locking members on the handle and the prying member, and means to engage and disengage said locking members, comprising a slidable lug, a slidable sleeve embracing said handle and connected to said lug, and resilient means to urge said lug and said sleeve in one direction.
